UNITED STATES PATENT OFFICE.

WYLLYS AVERY, OF SALISBURY, NEW YORK.

IMPROVEMENT IN WINDOW-BLIND FASTENERS.

Specification forming part of Letters Patent No. 33,563, dated October 29, 1861.

To all whom it may concern:

Be it known that I, WYLLYS AVERY, of Salisbury, in the county of Herkimer and State of New York, have invented certain new and useful Improvements in Window-Blind Fastenings; and I do hereby declare that the following is a full, clear, and exact description of the same, reference being had to the accompanying drawing, and to the letters of reference marked thereon.

In the annexed drawing, making a part of this specification, A represents a portion of the sash; and B a portion of the window-blind to be fastened. To the blind, and also to the sash, are secured two metallic pieces C C', which are made exactly alike, or otherwise, if desirable, and of the form or substantially the form represented in the figure. The positions of the pieces are reversed when they are secured in position for use, as is represented.

In using this fastener the window-sash is first raised and the shutters are then closed. The sash is then drawn down, when the piece C' catches into and locks the piece C upon

the shutter, as is shown in the figure. It is evident now that so long as the window remains down the shutters cannot be opened without breaking the locks, and that as soon as the sash is raised the shutters are free to be opened.

The form of fastener may be varied, and a piece of wood or metal may be placed between the shutter and the piece C in order to accommodate it to windows which vary in width from shutter to sash.

Having thus fully described my invention, what I claim as new, and desire to secure by Letters Patent, is—

The combination of the catch upon the shutter with that upon the sash, so arranged that when the sash is lowered the blind will be secured, and the converse, substantially as specified.

WYLLYS AVERY.
